FIG. 1.

FIG. 2.

FIG. 3.

FIG. 4.

INVENTOR

Frank Walter

BY
John Flam
HIS ATTORNEY

UNITED STATES PATENT OFFICE.

FRANK WALTER, OF LOS ANGELES, CALIFORNIA.

TELEPHONE AND CAP THEREFOR.

Application filed December 16, 1925. Serial No. 75,755.

This invention relates to a telephone receiver and especially such as is used for the translation of radio signals. Such telephones consist usually of a magnet that is energized in accordance with the received signals, and a diaphragm of magnetic material arranged to be affected by the magnet. In order to form an ear piece, a cap is provided for the device, which cap is usually screwed on close to the diaphragm, and is provided with an aperture through which the vibrations of the air, produced by operation of the diaphragm, can affect the ear.

It is common for enthusiasts in radio, and for those attempting to secure signals from distant points, to keep the head phones on the ears for long intervals at a time. Under such circumstances, due to the formation of a confined space between the ear and the diaphragm, moisture usually collects thereon; this is obviously undesirable not only because it offends the sense of cleanliness, but because it interferes with proper reception. It is thus one of the objects of my invention to overcome these disadvantages in a telephone, and especially by the provision of a cap for the diaphragm which is formed to prevent the accumulation of moisture. In this connection, my invention is not at all limited to applications to radio, but can generally be applied to all types of telephones.

My invention also assists materially in clarifying the sound produced by the receiver; and I have found it to be of especial benefit in connection with radio reception in which considerable power is available in the audio frequency circuit; as for example, in sets utilizing two or more audions. In such sets, the clarification is marked with my invention, and the volume of sound is yet sufficient for all purposes. It can be applied to loud speakers as well as to ear phones.

My invention possesses many other advantages, and has other objects which may be made more easily apparent from a consideration of several embodiments of my invention. For this purpose I have shown a few forms in the drawings accompanying and forming part of the present specification. I shall now proceed to describe these forms in detail, which illustrate the general principles of my invention; but it is to be understood that this detailed description is

not to be taken in a limiting sense, since the scope of my invention is best defined by the appended claim.

Referring to the drawings:

Figure 1 is a sectional view of a telephone embodying my invention;

Fig. 2 is a perspective view of a telephone fitted with my invention;

Fig. 3 is a sectional view of a modified form of cap that can be used with a telephone; and

Fig. 4 is a bottom view thereof.

In Fig. 1, I show a circular body or shell 11 of insulating material, forming the main support for all the operative parts of the telephone. In this is mounted a series of magnets 12 near the center of the shell, so as to affect in a well-understood manner, the diaphragm 13. This diaphragm rests on the top edge of the shell 11, which is usually provided with screw threads. The magnets 12 being permanently magnetized, prevent movement of the diaphragm away from the edges of the shell 11.

In accordance with my invention, I utilize a cap 14 that fits over the threaded edge of shell 11, and that defines a space 15 over the diaphragm of considerable height. Apertures 16 are provided in the sides to permit air to enter and leave the space 15, independently of the ear opening 17. The cap 14 can be conveniently made from soft rubber, and of such dimensions that it will telescope snugly over the shell 11. The threads 18 are illustrated on shell 11, to show that existing shells can be used, by removing the usual threaded cap and replacing it by the cap 14 of the present invention.

The use of earphones such as shown in Figs. 1 and 2 results in considerable advantages. For long intervals, the head set having such phones is comfortable. No moisture can collect on diaphragm 13, due to the circulation of the air past it through apertures 16. Furthermore, it is noted that the signals are clearer, much of the disturbing noise found in radio sets being absent. I believe this results from the provision of a large free space 15 between the diaphragm 13 and the ear. This space is defined by the thin walls of the cap.

While soft rubber is advantageous to use for the cap 14, so as to provide a comfort-

able "feel" on the ears, it is entirely feasible to use hard material, such as bakelite or other phenolic condensation product, or hard rubber. Such an embodiment is shown in Figs. 3 and 4. In this instance, the cap 19 has a series of oval holes 20, as well as internal screw threads 21, whereby it can be screwed on in place in a position similar to that shown in Figs. 1 and 2. The same principle of operation however, is present in this form as in that first described. In each form of cap, there are one or more radial openings which are intended to communicate with a space between the diaphragm and the cap.

I claim:

A cap for a radio telephone receiver of the diaphragm type, said cap having an opening adapted to conduct the sound waves produced by the receiver, said cap extending over the diaphragm, the cap and said diaphragm defining a large, free space immediately interposed between the said opening and the surface of substantially the entire diaphragm, said cap having radial openings connecting said space directly with the external atmosphere.

In testimony whereof I have hereunto set my hand.

FRANK WALTER.
